UNITED STATES PATENT OFFICE.

GEORGE W. COLLAMORE, OF WINCHESTER, MASSACHUSETTS.

TELEPHONE ATTACHMENT.

1,261,705.

Specification of Letters Patent. Patented Apr. 2, 1918.

Application filed May 23, 1916. Serial No. 99,320.

To all whom it may concern:

Be it known that I, GEORGE W. COLLAMORE, a citizen of the United States, and a resident of Winchester, in the county of Middlesex 5 and State of Massachusetts, have invented a new and useful Improvement in Telephone Attachments, of which the following is a specification.

My invention relates to telephone attachments, and more especially to means for supporting the receiver during the use of the telephone.

The object of my invention is to provide a simple and easily adjustable device whereby 15 the receiver may be held in proximity to the ear of the user of the telephone and thereby permit such user to have the free use of both hands for the purpose of making notes, etc., during the conversation.

One embodiment of my invention is shown 20 in the accompanying drawings, in which Figure 1 is an elevation of my improved attachment secured in position to a desk-set, and Fig. 2 is a plan view showing the receiver supported by said attachment.

In the particular drawings selected for 25 more fully disclosing my invention, the telephone desk-set is shown in dotted lines and comprises as usual the standard 1, receiver 2, and transmitter 3. A split-ring 4, shown 30 in the present instance as hinged at 5, embraces the standard and is clamped thereto by the wing-screw 6. The ends or vertical shank portions 8 of a wire loop 7 pass 35 through and tightly fit into two vertical holes in a lateral extension of said split-ring, so that the loop may readily be raised or lowered and maintained in the desired position with respect to said ring. The wire 40 loop 7 comprises two downwardly-curved portions 9, 10, shaped to receive the larger

and smaller ends respectively of the horn 2, the portion 9 being lower than the portion 10, so that the receiver may be held in a substantially horizontal position. 45

The device as a whole may be raised or lowered with respect to the telephone by means of the ring 4 and wing-screw 6, the receiver-supporting loop may as aforesaid be adjusted vertically with respect to the ring, 50 and preferably said loop is made of flexible material such as wire, so that it may be adjusted laterally by slightly bending the same in order to bring the receiver, when resting therein, to the proper position adjacent to 55 the ear of the user.

It will be understood that various modifications may be made in the construction shown and particularly described herein without departing from the spirit of my invention. 60

I claim:

A device for supporting a telephone receiver in proximity to the ear of the user, comprising in combination a clamp adjustably and removably secured to the standard 65 of the telephone set, said clamp having a lateral extension provided with vertically arranged holes, and a side bracket for holding the receiver, said bracket consisting of a loop 70 of flexible wire having its upper end bent to hold the receiver and terminating in two vertical shank portions, said shank portions being substantially parallel to the standard 75 and fitting into the holes in said clamp.

In testimony whereof, I have hereunto subscribed my name this 22nd day of May, 1916.

GEORGE W. COLLAMORE.

Witnesses:

GEO. K. WOODWORTH,
E. B. TOMLINSON.
